UNITED STATES PATENT OFFICE.

AMOS HENRY SWITZER AND LUKE MICHAEL SWITZER, OF SUTTON WEST,
CANADA.

COMBINED LEGGING AND SOCK.

No. 806,939.

Specification of Letters Patent.

Patented Dec. 12, 1905.

Application filed October 1, 1904. Serial No. 226,871.

To all whom it may concern:

Be it known that we, AMOS HENRY SWITZER and LUKE MICHAEL SWITZER, shoemakers, residing at the town of Sutton West, in the county of York, in the Province of Ontario, Canada, have invented certain new and useful Improvements in a Combined Legging and Sock, of which the following is a specification.

Our invention relates to improvements in combined leggings and socks, patented to us in the Dominion of Canada under No. 87,665 on the 7th of June, 1904, and application for which was filed in the United States Patent Office under Serial No. 190,047 on the 21st of January, 1904; and the object of the present invention is, first, to form a blank for the sock, so that the liability of ripping of the sewing at sewed notches of toe and heel will be reduced to a minimum, and, secondly, to provide means for connecting the legging to the sock, whereby the sock and legging may be worn with or without the rubber shoe and in which the rubber shoe may be readily fitted and snugly held between the bottom of the legging and sock; and it consists, essentially, first, of a sock formed of a blank, having the notches cut in such a manner as when sewed together the slits formed thereby will not come opposite each other, and, secondly, of attaching the legging to the sock at the upper edge of the sock and allowing of the bottom end of the legging to extend as a flap below the connection of the legging to the sock, and of a flap for the legging provided with notches whereby the lace of the sock may be continued from the front of the sock up through the notches in the flap and hole in the legging up along the front of the legging, and a separate lace for connecting the bottom of the legging together, the parts being otherwise constructed and arranged as hereinafter more particularly explained.

Figure 1 is a perspective view showing our improved combined legging and sock, the bottom flap of the legging being shown in dotted lines turned up as it would be to enable the rubber shoe to be placed in position. Fig. 2 is an enlarged perspective view showing the legging open. Fig. 3 is a detail of the blank. Fig. 4 is a front view showing the manner in which the notches at the toe are placed on each side of the circular seam. Fig. 5 is a similar view showing the way the notches at

the heel are placed in relation to each other on each side of the central seam. 55

In the drawings like letters of reference indicate corresponding parts in each figure.

A is a blank. The blank A is provided with substantially V-shaped toe and heel notches a and a' and side toe and heel notches a² and a³. The notches a² of the toe are located at unequal distances from the central notches a, and the notches a³ are located at unequal distances from the center of the notch a', so that when the seams are formed on the side of the notches a and a², as indicated in Fig. 4 at 2, the sides of the notches a² of the toe portion when sewed together do not come opposite to each other, as indicated at 3. The notches a³ are likewise shown, as indicated in Fig. 5, so that the sewed notches, as indicated by 4, do not come opposite each other. By this means it will be readily seen that the liability of ripping of these notches when they are opposite each other, as described in our former patent, is reduced to a minimum. Especially should one of the sewed notches rip there would not be any liability of the other on the opposite side of the central seam being ripped, seeing that they are not opposite each other, and the same thread would not pass from one to the other. 70

The blank A is formed up, as indicated in Figs. 1 and 2, with a central slit A', provided with holes 5 at one side and hooks 6 at the other, through which pass the lace B, as indicated, such lace extending upwardly to the top of the sock and passing inwardly to and through a hole 5' in the sock, whence it extends outwardly and passes through a hole 7' 90 in the legging portion C.

D is the front flap of the legging, which is suitably sewed to one edge of the front opening, and D' is the lower portion of the front flap, which is formed separately from the portion D by means of a notch d. It is through the notch d that the lace B passes when the portion D' is turned inwardly underneath the opposite edge of the legging at the opening when the legging is closed at the front, as indicated in Fig. 1. 100

We provide a row of lace-holes 8 on the overlying edge C' of the legging and hooks 9 on the other edge C'; but it will of course be understood that holes may be provided at 105 each edge C' and C' at the opening of the

legging or all hooks or any other suitable form of fastener for the lace. The lace which passes up through the openings and hooks is the lace B, which passes through the holes 7 5 to the outside of the legging, as hereinbefore referred to.

The top of the laces B and B' are held by any suitable form of fastener, which it is not necessary here to describe.

10 The legging is secured to the top edge of the sock by a row or rows of stitching E, so that a depending flap C' is formed around the ankle portion of the sock. In the front edge of the flap C' at each edge of the opening we 15 provide a row of lace-holes 10 and hooks 11, and in the row of lace-holes we provide a lace B', which when the flap D' is folded under the flap C' is hooked upon the hooks 11 and tightened. Of course eyelets may be substituted 20 for hooks. It will, however, be understood that the legging and sock will be completely laced together by the lace B, with of course the exception of the portion C', and this is left loose, so that it may be turned up, as indicated in Fig. 1, in order that the rubber 25 shoe may be brought up upon the sock nearly to the top thereof, whereupon the flap C' may be turned down and laced tightly, as hereinbefore described and as shown in Fig. 1.

30 To lumbermen and those accustomed to wearing this class of sock and legging the advantages will be apparent. After a man has been out with his rubber shoes on he can when he comes into the shanty by simply unlacing the lace B' turn up the flap C' and take off his rubber shoe. The leather sock of the legging will of course be still intact and he can go about the shanty or indoors much more comfortably than if he had to keep the rubber shoe on. Upon going out again all he 40 has to do is to put the rubber shoes on and replace the bottom part of the legging over the top of the rubber shoe.

What we claim as our invention is—

45 1. In a combined legging and sock, a blank having the central V-shaped notch, and an irregularly-placed notch on each side of the central notch, whereby when the central seam is made through the central notch and opposing 50 edges of the blank the seam of the cross-notches will end in the central seam at points remote from each other as and for the purpose specified.

2. The combination with the sock having the 55 central slit and lace-holding means on opposite sides of the slit, of the legging secured in-

termEDIATE of its length to the top of the sock and having the overlapping portion or flap extending over the ankle portion of the sock, said legging having a front opening and lace-holding means on opposite sides of said opening and a hole extending through the front of the legging near the top of the sock, whereby the lace of the sock is extended through the lace-holding means of the legging as and for the purpose specified.

3. The combination with the sock having the central slit and lace-holding means on opposite sides of the slit, of the legging secured intermediate of its length to the top of the sock 7c and having the overlapping portion or flap extending over the ankle portion of the sock, said legging having a front opening and lace-holding means on opposite sides of said opening and a hole extending through the front of the legging near the top of the sock, whereby the lace of the sock is extended through the lace-holding means of the legging, and the front flap of the legging provided with a notch, whereby a lower supplemental flap is formed 80 and the lace of the sock is carried through to the lace-holding means at the front of the legging as and for the purpose specified.

4. The combination with the sock having the central slit and lace-holding means on opposite sides of the slit, of the legging secured intermediate of its length to the top of the sock and having the overlapping portion or flap extending over the ankle portion of the sock, said legging having a front opening and lace-holding means on opposite sides of said opening a hole extending through the front of the legging near the top of the sock, whereby the lace of the sock is extended through the lace-holding means of the legging, the front flap 90 of the legging provided with a notch, whereby a lower supplemental flap is formed and the lace of the sock is carried through to the lace-holding means at the front of the legging and a lace passing through the lace-holding 100 means on one edge of the overlapping flap or portion of the legging and adapted to be fastened to the lace-holding means on the supplemental flap of the legging to fasten the legging completely together as and for the purpose specified.
